UNITED STATES PATENT OFFICE.

THOMAS E. MCCOY, OF ICKESBURG, PENNSYLVANIA.

DESIGN FOR AN ANTISKID-CHAIN.

50,026.

Specification for Design.

Patented Dec. 12, 1916.

Application filed February 29, 1916. Serial No. 81,271. Term of patent 7 years.

To all whom it may concern:

Be it known that I, THOMAS E. McCoy, a citizen of the United States, residing at Ickesburg, in the county of Perry and State of Pennsylvania, have invented a new, original, and ornamental Design for Antiskid-Chains, of which the following is a specification, reference being had to the accompanying drawing, forming a part thereof.

The figure is a plan view of an anti-skid chain, showing my new design.

I claim:

The ornamental design for an anti-skid chain, as shown.

THOMAS E. MCCOY.
